UNITED STATES PATENT OFFICE.

JOHN KONAR, OF CHICAGO, ILLINOIS.

INTERNAL-COMBUSTION CHAMBER FOR ENGINES.

1,342,449.

Specification of Letters Patent.

Patented June 8, 1920.

Application filed August 14, 1916. Serial No. 114,865.

To all whom it may concern:

Be it known that I, JOHN KONAR, a citizen of the United States of America, and a resident of Chicago, in the county of Cook, 5 State of Illinois, have invented certain new and useful Improvements in Internal-Combustion Chambers for Engines, of which the following is a specification.

My invention relates to improvements in 10 internal combustion engines, and the object of my invention is to afford a simplified and efficient intake passage arranged for a two way admission, inclined to whirl the charge, and adapted to reduce the violence of the 15 hammering of the valve, and to dispose of carbon deposits and of pockets and projections in the chamber. All as will hereinafter more fully appear.

In the accompanying drawings:— 20 Figure 1 is a vertical section of a combustion chamber of a gas engine embodying my invention.

Fig. 2 is a transverse detail section of Fig. 1, shown on a line and in a direction 25 indicated by arrow 26, and

Fig. 3 is an enlarged top view of the 30 inlets 24 in the disk 21 illustrating the turbine blades 27 and indicating by shade lines the slanting surfaces adjacent the ports 24.

The port 16 in my selected exemplification of a gas engine may be fitted with any 35 of the suitable known charging attachments.

The port has a recessed extension 17 partly surrounding the throat 15, and therefrom 40 ordinarily separated by the wall 18 and by the tubular rim 19 of the throttle 20, which is rotatively fitted in the throat.

The rim has a number of ways 22, adapted to register with a number of similar ways 45 in the wall of the throat to promote the whirling of the charge and a rapid opening and closing of said port and its extension through a fractional turn of the throttle by operating its crank 23.

The port 16, its extension 17 and the ways 50 22 have a tangential inclination to the throat 15, and afford thereby a whirl inducing intake passage for the charge. The discharge ends of the port 16 and of the extension 17 are disposed to empty into the throat 15 in the same tangential direction but from opposite sides of the periphery of the throat and produce by such distribution a vortex of a more uniform circumgyration.

When fed by suction with a four cycle 55 engine through the port 16, the fuel-mixture rushes by its tangential inertia into the peripheral space of the throat 15, turns therein scroll-fashioned to the centrally disposed vent 7, and pours downward as a 60 whirl, gyrating centrifugally alongside the periphery of the chamber 12 and brushing centripetally over the top of the receding piston 11 to form thereon a turning column. 65

A disk 21 above the throat has a diaphragm with a number of inlets 24, ordinarily closed by the throttle, but adapted to register with similar inlets in the top of the throttle and to establish thereby a rapid 70 communication with the outside when the throttle is turned that way. The inlets have adjacent slanting surfaces and may be provided with turbine blades 27 to promote a swift turning of the air in the throat 75 15 during the suction stroke and to create vortex of air above the vent 7. In the making of the disk 21 the port-openings 24 are preferably cast without adjacent slanting surfaces for reasons of difficulties in running the molten cast-iron into thin edges without chilling the edges into hardness too difficult for machining. The slanting surfaces are more conveniently provided by forming sheet metal into turbine blades 27 80 and then inserting the blades in the ports 24 during the casting process or by any other convenient manner such as welding, riveting or the like. The slanting surfaces, as indicated in Fig. 3 by shade lines on the 85 turbine blades 27, are disposed and inclined correspondingly to collectively turn the charge in one common direction around the common axis of the throat and the cylinder. 90 95

When fed by the port 16 the fuel charge, inclined by the ways 22, streams tangentially into the peripheral space of the throat and is deflected by the wall of the throat into a centripetal scroll-fashioned course to turn above the vent 7 into a vortex of fuel mixture. The deflecting and turning function of the circular throat 15 and the narrower vent 7 produces a uniformity of turning with the otherwise irregularly whirling vortex and insures thereby a uniform centrifugal spreading of the eddying charge 100 below the vent 7, when in the chamber 12 105

of the cylinder 10 a vacuum is provoked by the crank stroke of the piston 11, that is generally connected to a crank shaft by the rod 6.

- 5 Below the vent 7 the circumfusing charge spreads by centrifugal force toward the wall of the cylinder 10, and then hugging the wall descends as a peripherally circumfluent tube toward the retreating piston 11. Mean-
10 while the speed of rotation of the lower tubular end of the charge is slowed down by the friction on the wall of the cylinder and by impact against the piston; simultaneously the thereby hindered tubular end
15 loses centrifugal force and is pushed by the faster more centrifugal later arrival into a centripetal tub-bottom like transition to subjoin a base to a vapor column, that is rising core like within said peripherally cir-
20 cumfluent tube of later arriving charge.

Whenever during the later part of the suction stroke the fuel is cut off by a suitable provision with the charging attachment and only a portion of fuelless air is
25 admitted to the port 16 on top of the pre- ceded fuel charge, or when the port 16 is closed and the throttle is switched open for a whiff of air through the turbine bladed inlets 24, a fuelless whirlwind sweeps be-
30 hind the gyrating fuel charge, produces a vortex above the vent 7, and spreads below the vent centrifugally to descend tubularly between the fuel core and the walls of the cylinder to contract on the receding piston
35 to a tub-bottom form and having thus en- enveloped the preceded fuel charge to remain as last arrival in that enveloping relation during the brief moment of compression. During compression, after the vent 7 is
40 sealed, inertia continues to keep the peripherally arrived cooler and more weighty air in a circumfluent centrifugal state, while lack of centrifugal force with the lighter fuel nucleus explains its centripetal perse-
45 verance. The vapor of the nucleus had preceded the later arriving air by a pilot- ing passage over the hot surfaces and be- came lightened through heat-expansion be-
50 fore it settled centripetally. Therefore the nucleus has less weight than the air that arrived later over partly cooled surfaces and therefore the slower turning lightweighted nucleus does not mix during the brief mo-
55 ment of compression with the heavier faster turning air envelop.

Prolonging the fuelless air admission into more cycles, as for instance by adding a cycle fed by plain air to a four cycle engine, what is commonly called a six cycle
60 gearing, affords an efficient air cooling of the chamber. The vortex whirls all the air successively over all the overheated surfaces to hug them subsequently with an intimate cooling contact before filling into the in-
65 terior space of the chamber; this air cool-

ing efficiency is absent with an ordinary gas engine.

The throttle is operated positively by any of the suitable known transmissions to close the fuel and air ports in timed relation to 70 the piston and to open them alternately.

The whirling charge brushes the heated surfaces of the chamber, cooling them evenly and simultaneously itself getting warmed and vaporized more uniformly than 75 by ordinary charging. By proper setting of a suitable charging attachment a rich fuel mixture may be fed ahead to produce the nucleus within the last arrived, by centrifugal force peripherally localized, air-en- 80 envelop. Air, water mist or their mixture may form the protective lining envelop around the fuel nucleus and afford thereby during firing a productive internal cooling and a chamber free of carbon deposit by in- 85 stantaneous consumption. The envelop immediately returns the received heat as additional energy by its own expansion through a heat that is otherwise wasted by the present unproductive cooling methods. 90

Suitable means for ignition, as for instance a spark plug 9, has to be arranged to reach the nucleus through the envelop.

The throttle in a closed position affords a sufficient sealing of the cylinder dur- 95 ing low pressures. Ordinarily the throttle seals the cylinder during the compression, and permits a delayed and therefore less violent seating of the puppet valve 8, which closes the vent 7 and seals the explosion 100 chamber for firing purpose securely, thus sparing the throttle high pressure and permitting its light fitting.

The stem of the valve 8 is reciprocally inserted into a sleeved neck extending pref- 105 erably from the disk 21. The valve and the throttle may be suitably operated by various known means to move with each cycle into the respective positions of fuel intake and air admission. Prolonging the dura- 110 tion of fuel intake with each cycle will limit the time left for air admission and will reduce the proportion of the latter,—and vice versa.

The throttle when geared four cycle fash- 115 ion to the crank shaft and switched with the inlets 24 open to the outside during the return stroke, affords an exhaust and permits the omission of an extra outlet. A more complex exhaust may be arranged by 120 a separate exhaust port near the head of the cylinder.

The fuel intake may be directed through the inlets 24 by attaching thereto a suitable known charging device, and the port 16 125 may then be used for air admission and for exhaust.

For charging the engine as a two cycle type, the port 16 and the inlets 24 are suitably fed under pressure from a properly 130

arranged source of fuelless air. The fuel may be injected otherwise at the port 16 into the ingoing compressed air during the end course of the crank stroke. The fuel mixture is then subject to the afore set forth deflecting and turning function of the throat 15 and the thereto tangentially inclined ways 22 and turns into a vortex above the vent 7. The valve 8 is ordinarily dispensed with the engine in a two cycle service. The opening 5', near the crank end of the cylinder and sealable by the piston, serves as an exhaust port. The gyration induces the charge to pour down as a whirling body through the vent 7 into the space of the chamber 12, which is then open to full capacity with the piston pulled down by the piston rod 6, that is suitably operated otherwise. There are no stray shoots of the fuel getting lost through the exhaust opening, especially when a whirl of air is admitted ahead of the fuel charge by delaying the fuel admission into the air intake or by admitting said whirl through the turbine-bladed inlets 24 of the throttle 20, which is suitably otherwise operated to close and open into the respective positions. The crank case 14 with the opening 13 may be arranged in usual manner for compressing the charge.

Having thus fully described my said invention, what I claim as new and desire to secure by Letters Patent, is:—

1. In an internal combustion engine a cylinder with a head thereon, within the cylinder a movable piston, within the cylinder head a throat for turning the charge into a vortex, in the casing of said throat a number of ports open for a suitable fuel admission and having adjacent slanting surfaces to turn the charge into said vortex, between the throat and the cylinder and thereto axially alined a circular vent, said vent forming a narrowing to the lower end of said throat to constrict the peripheral irregularly turning portion of said vortex into a smaller radius and a more uniform circumrotation, said vent having a smaller circumference than the bore of the cylinder to assure a more uniform circumfusion of said vortex within said cylinder, a valve adapted to seal said vent, means to ignite the charge and a suitable exhaust.

2. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel admission and having a discharge into said throat, with the discharge end of said port a tangential incline to the periphery of said throat whereby said discharge end is adapted to direct the charge to stream tangentially through said periphery into the peripheral space of said throat, a throttle within the

space of said throat, between the throat and the cylinder and thereto axially alined a circular vent, said vent forming a narrowing to the lower end of said throat to constrict the peripheral irregularly turning portion 70 of said vortex into a smaller radius and a more uniform circumrotation, said vent having a smaller circumference than the bore of the cylinder to assure a uniform circumfusion of said vortex within said cylinder, a 75 valve adapted to seal said vent, means to ignite the charge and a suitable exhaust.

3. In an internal combustion engine a cylinder with a head thereon, within the cylinder a movable piston, within the cylinder 80 head a throat for turning the charge into a vortex, in the casing of said throat a number of ports open for a suitable fuel admission and having adjacent slanting surfaces to turn the charge into said vortex, between 85 the throat and the cylinder and thereto axially alined a circular vent, said vent forming a narrowing to the lower end of said throat to constrict the peripheral irregularly turning portion of said vortex into a smaller 90 radius and a more uniform circumrotation, said vent having a smaller circumference than the bore of the cylinder to assure a more uniform circumfusion of said vortex within said cylinder, a valve adapted to 95 seal said vent, means to ignite the charge and an exhaust near the crank end of the cylinder and sealable by the piston.

4. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel admission and having a discharge into said throat, with the discharge end of said port a tangential incline to the periphery of said throat whereby said discharge end is adapted to direct the charge to stream tangentially 110 through said periphery into the peripheral space of said throat, between the throat and the cylinder a thereto axially alined circular vent, a puppet valve adapted to seal the cylinder against said vent, means to ignite the 115 charge and a suitable exhaust.

5. In an internal combustion engine a cylinder with a head thereon, within the cylinder a movable piston, within the cylinder head and in axial alinement with the cylinder 120 a throat for turning the charge into a vortex, in the wall of the cylinder head a port with an opening for a suitable fuel admission and having a discharge into said throat, with the discharge end of said port 125 a tangential incline to the periphery of said throat whereby said discharge end is adapted to direct the charge to stream tangentially through said periphery into the peripheral space of said throat, a throttle within the 130

throat and adapted to close and open said port, means to ignite the charge and a suitable exhaust.

6. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel admission and having a discharge into said throat, with the discharge end of said port a tangential incline to the periphery of said throat whereby said discharge end is adapted to direct the charge to stream tangentially through said periphery into the peripheral space of said throat, in the cylinder head another passage between the outside and said throat, a throttle within the throat and adapted to close and open said passages, means to ignite the charge and a suitable exhaust.

7. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel admission and having a discharge into said throat, with the discharge end of said port a tangential incline to the periphery of said throat whereby said discharge end is adapted to direct the charge to stream tangentially through said periphery into the peripheral space of said throat, between the throat and the cylinder a thereto axially alined vent, means to ignite the charge and an exhaust near the crank end of the cylinder and sealable by the piston.

8. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel admission and having a discharge into said throat, with the discharge end of said port a tangential incline to the periphery of said throat whereby said discharge end is adapted to direct the charge to stream tangentially through said periphery into the peripheral space of said throat, a throttle within the throat and adapted to close and open said intake passage, means to ignite the charge and an exhaust near the crank end of the cylinder and sealable by the piston.

9. In an internal combustion engine a cylinder with a head thereon, within the cylinder a movable piston, within the cylinder head and in axial alinement with the cylinder a throat for turning the charge into a vortex, in the wall of the cylinder head a port with an opening for a suitable fuel ad-

mission and having a discharge into said throat, with the discharge end of said port a tangential incline to the periphery of said throat whereby said discharge end is adapted to direct the charge to stream tangentially through said periphery into the peripheral space of said throat, from said port an extension partly surrounding the throat and separated therefrom by a wall, in said wall and tangentially disposed to the periphery of the throat a number of ways into the throat from said port and its extension, means to ignite the charge and a suitable exhaust.

10. In an internal combustion engine a cylinder with a head thereon, within the cylinder a movable piston, within the cylinder head and centrally disposed in alinement to the longitudinal axis of the cylinder a circular throat for turning the charge into a vortex, into the throat a number of sealable passages, one of said passages open for a suitable fuel admission, and another open to the outside, a throttle rotatably fitted within said throat and adapted to close and open said passages, within each of said passages an inclined plane to promote the charge into turning around the axis of the cylinder, means to ignite the charge and a suitable exhaust.

11. In an internal combustion engine a cylinder with a head thereon, within the cylinder a movable piston, within the cylinder head and centrally disposed in alinement to the longitudinal axis of the cylinder a circular throat for turning the charge into a vortex, above the throat a diaphragm with sealable inlets open to receive a suitable charge, with the inlets an inclined plane to promote the charge into turning around the axis of the cylinder, means to ignite the charge and a suitable exhaust.

12. In an internal combustion engine a cylinder with a head thereon, within the cylinder a movable piston, within the cylinder head and centrally disposed in alinement to the longitudinal axis of the cylinder a circular throat for turning the charge into a vortex, above the throat a diaphragm with inlets open to receive a suitable charge, below the diaphragm a circular throttle having inlets adapted to register with the inlets in said diaphragm, said throttle rotatably fitted within the throat and adapted to close and open said diaphragm, with said inlets an inclined plane to promote the charge into turning around the axis of the cylinder, means to ignite the charge and a suitable exhaust.

13. In an internal combustion engine a cylinder, within the cylinder a movable piston, to the cylinder and alined therewith to a common longitudinal axis an ante-chamber as latitude for turning the charge into a vortex around said axis, in the casing of

said ante-chamber and open for a suitable fuel admission a number of ports having an adjacent slanting surface inclined to turn the passing charge into said vortex around said axis, from said ante-chamber into said cylinder and narrower than the bore of said cylinder a circular vent alined around said axis to circularly constrict said vortex toward said axis for a centrifugally circum-

fusing envelop-forming whirl into the cylinder, a valve adapted to seal said vent, means to ignite the charge and a suitable exhaust.

Signed at Chicago, Illinois, this 12th day of August, A. D. 1916.
